UNITED STATES PATENT OFFICE

151,574

DESIGN FOR A DOOR KNOCKER

John F. Williams, Hingham, Mass.

Application November 6, 1946, Serial No. 134,544

Term of patent 14 years

(Cl. D10—7)

To all whom it may concern:

Be it known that I, John F. Williams, a citizen of the United States of America, residing at Hingham, in the county of Plymouth and State of Massachusetts, have invented a new, original, and ornamental Design for a Door Knocker, of which the following is a specification, reference being had to the accompanying drawings, forming part thereof.

Figure 1 is a perspective view of a door knocker embodying my new design.

Figure 2 is a side elevation of the door knocker shown in Figure 1.

I claim:

The ornamental design for a door knocker, as shown.

JOHN F. WILLIAMS.
